(57) CLAIM

The ornamental design for a unmanned data gathering aircraft, as shown and described.

DESCRIPTION

FIG. 1 is an environmental perspective view of an unmanned data gathering aircraft showing our new design;
FIG. 2 is a front elevational view thereof;
FIG. 3 is a top plan view thereof;
FIG. 4 is a left side elevational view thereof, the right side being a mirror image thereof; and,
FIG. 5 is a rear elevational thereof.

The underside of the aircraft is unornamented.

The broken line showings of a propeller and of removable fuselage modules throughout the Figures are for illustrative purposes only and form no part of the claimed design.
